UNITED STATES PATENT OFFICE.

WILLIAM KELLEY, OF BALTIMORE, MARYLAND.

LOCOMOTIVE HEAD-LIGHT.

SPECIFICATION forming part of Letters Patent No. 234,410, dated November 16, 1880.

Application filed March 24, 1880. (No model.)

To all whom it may concern:

Be it known that I, WILLIAM KELLEY, of the city of Baltimore and State of Maryland, have invented a new and useful Improvement 5 in Signals for Locomotive Head-Lights; and I do hereby declare that the following is a full, clear, and exact description thereof, which will enable others skilled in the art to which it appertains to make and use the same, reference being had to the accompanying drawings, and to the letters of reference marked thereon.

My invention relates to a signal which may be exhibited, as desired, in front of the lantern to indicate that the train is immediately followed by another, or as a danger-signal, or for other purposes.

This invention is designed for the use of railroad companies, and is intended to effect a saving to said companies by dispensing with lamps of different kinds and the oil necessary to supply them; and the invention consists, first, in combining with the head-light lantern, at the front parts thereof, on either side of the 25 rim, a small box having front and side panes of glass, which will give front and side lights from the lamp placed within the lantern.

The invention consists, secondly, in providing an opaque-leaved cover for the front and side parts of the said boxes and in the mechanism whereby the said cover is manipulated from the cab, or otherwise, as may be desired.

In the accompanying drawings, Figure 1 is a perspective view of the invention. Fig. 2 is 35 a rear view. Figs. 3 and 4 show details of the invention. Fig. 5 is a view in horizontal transverse section, showing the means by which the light from the lantern is reflected through the front and side panes of the side boxes.

Similar letters of reference indicate similar parts in all the views.

A is the head-light lantern, of which *a* is the front rim. The lamp is placed within the lantern in the ordinary manner, the lantern being provided with the usual reflector A', Fig. 5.

B B represent the boxes placed at the front of the lantern, which boxes have openings at their fronts and outer sides covered with white glass. Colored panes of glass are placed over 50 the white panes of glass, and may be either stationary or removable, being made to slide

either endwise or sidewise, as may be desired. It is to be understood that those portions of the face of the main lantern behind the boxes are removed, so that the light from the lamp 55 on the inside of the main lantern will be seen through the fronts and sides of the boxes.

To the sides of the main lantern are hinged opaque-leaved covers C, to which are attached rods D, which run back toward the cab. 60

When it is desired to expose the front and side lights of the boxes the leaved covers are drawn back from the position shown in Fig. 1, so as to cause them to lie flat against the sides of the main lantern. This may be done 65 by means of the rods D, or, if the rods are not used, it may be done by simply moving the leaved covers by hand. Under the boxes may be placed catches c, and similar catches may be placed at the sides of the main lantern 70 for holding the leaved covers in their closed and opened positions. This construction is shown in Figs. 3 and 4.

Behind the main lantern may be placed pockets d, for holding the colored panes when 75 made removable. Glasses of various colors may be provided, such as red, green, or other colors in use on railroads as signals for different purposes.

By means of this invention brilliant side 80 and front colored lights are obtained in a simple manner, and the necessity of using a large number of lanterns of different descriptions is avoided.

The invention may be applied to any lantern now in use.

I am aware that it is not new to attach bull's-eye lenses to the upper front portions of the face of a head-light lantern, which show front lights from the flame within the lantern. 90

I am further aware that signal head-lights have been used heretofore having a chamber outside of each side thereof, which chambers have front and side panes of glass, through which the light from the main lantern is reflected; but such a construction requires the aid of a mirror or reflector within each of said chambers in order to direct the rays of light. 95

In my patent No. 209,405, dated October 29, 1878, are shown frames attached to the sides 100 of the front rim for showing side lights, the front and side lights being transmitted through

colored-glass panes hinged or leaved together in a frame, somewhat similar in construction to the opaque-leaved covers employed by me for concealing the front and side lights in my

5 present invention. Such previous invention, therefore, I do not claim herein; but,

Having described my invention, I claim—

1. In combination with a lantern, A, having portions of its front face removed, the
10 boxes, B, attached to said face at either side of the rim in front of said openings, and provided with front and side glass panes, substantially as described, whereby the light within the lantern is seen through the panes
15 of the boxes, as set forth.

2. In combination with the lantern A and boxes B, affixed to the face thereof, the opaque-leaved covers C, hinged to the lantern, substantially as specified.

3. In combination with the lantern A, boxes 20 B, and opaque-leaved covers C, hinged to the lantern, the rod D, leading toward the cab for manipulating the hinged and leaved covers, substantially as specified.

In testimony whereof I have hereunto subscribed my name this 24th day of March, 1880.

WILLIAM KELLEY.
